UNITED STATES PATENT OFFICE.

CLYDE A. AUNGER, OF SAN FRANCISCO, CALIFORNIA.

ARTIFICIAL KNEE-JOINT.

1,074,233.

Specification of Letters Patent. Patented Sept. 30, 1913.

Application filed April 2, 1913. Serial No. 758,704.

To all whom it may concern:

Be it known that I, CLYDE A. AUNGER, a citizen of the United States, residing in the city and county of San Francisco and State 5 of California, have invented a new and useful Improvement in Artificial Knee-Joints, of which the following is a specification.

My invention relates to artificial knee joints wherein a leg portion is pivotally secured to a stump portion, the said leg portion being operated by a supporting suspender attached to a back check which in turn 10 controls the forward movement of the said leg portion and the object of my invention 15 is to provide improved means that shall be simple of construction and operation and adapted to operate in conjunction with the supporting suspender for the purpose of controlling the forward movement of the 20 leg portion.

For a full and clear comprehension of my invention reference should be had to the drawings forming a part of this specification wherein like numerals of reference designate 25 similar parts throughout the said specifications and drawings and in which—

Figure 1 is a side elevation of an artificial leg and suspenders the lower part of the leg portion being broken away. Fig. 2 is a front 30 elevation of Fig. 1. Fig. 3 is a broken rear view of the stump portion showing the manner in which the suspenders are secured thereto. Fig. 4 is an enlarged broken sectional view of the knee joint in a standing 35 or vertical position. Fig. 5 is a similar view showing the position of the several parts when the knee is bent as in a sitting position. Fig. 6 is a broken rear view of the knee joint in elevation.

40 My invention consists mainly of a hollow stump portion 1 which is adapted to receive the stump of an amputated leg where the limb has been amputated above the knee. A leg portion 2 is pivotally secured to the 45 stump portion 1 by means of the knee bolt 3, the said knee bolt 3 being rigidly secured at each end thereof to vertical extensions on the upper portion of the leg 2. A back check 4, having an upper vertical offset portion 4' 50 and a central horizontal portion 6, is rigidly secured to the upper back portion of the leg 2, the upper vertical portion 4' of the said back check 4 resting against the knee bolt 3 within the hollow stump 1.

A strap 5 is secured to the horizontal portion 6 of the back check 4, and after passing over a roller 7, that is rotatably mounted within a horizontal slot 8 within the front wall of the stump 1, and under a retaining strap 10, is secured to the front lower ends 55 of two supporting suspenders 9 that pass over the shoulders of the wearer and are secured to the back portion of the stump 1 as illustrated in Fig. 3 of the drawings. The retaining strap 10 is secured to and encircles 60 the top of the stump 1 for the purpose of strengthening that member and also for the purpose of retaining the check strap 5 against the stump 1. A slot 12 is provided in the lower back portion of the stump 1 70 for the reception of the back check 4. The lower end of the slot 12 is padded as at 14 with felt or any other suitable shock absorbing material.

By referring to Fig. 4 it will be observed 75 that when the leg 2 is planted firmly on the ground it will serve as a support for the stump 1. The stump 1 will be prevented from rotating forward on the knee joint 3 by the back check 4 against which the padded 80 end 14 of the slot 12 in the stump 1 is resting. It is apparent from the foregoing description that while the leg portion 2 is free to swing backward on the knee bolt 3 when the said leg is raised from the ground it is 85 prevented from swinging forward from the position shown in Fig. 4 by the back check 4.

The operation of the artificial knee joint in walking is as follows: We will assume, for purposes of illustration, that the right 90 leg is the one that has been replaced by the artificial limb. In taking a step forward with the left leg the weight of the body of the wearer is supported by the artificial right leg, the foot of which is planted firmly 95 on the ground. As the body bends forward in stepping out with the left leg the weight of the body is brought forward of the knee joint, and consequently of the knee bolt 3, of the artificial right leg. In stepping out 100 with the left leg the tendency of the stump 1 of the right leg is to rotate forward upon the knee bolt 3 which would precipitate the wearer forward if it were not checked by the padded end 14 of the slot 12 through which 105 the back check 4 projects. When the step forward with the left foot is finished and the weight of the body transferred thereto

the next action in walking would be to bring the artificial right leg forward. As the right leg is raised from the ground and the stump portion 1 is brought forward by the stump 5 of the right leg, the leg 2 is raised from the ground and is, consequently, free to swing forward on the knee bolt 3. This forward movement of the leg 2 is controlled and facilitated by means of the suspenders 9 which 10 pass over the shoulder of the wearer and are secured to the strap 5, the said strap being in turn secured to the horizontal portion 6 of the back check 4. The forward movement is accomplished by giving a slight forward motion to one of the shoulders which motion is communicated, by means of the straps 9 and 5 and the back check 4, to the leg 2 so that the said leg 2 may be brought forward with a speed directly proportionate 15 to the movement of the shoulder. In this manner a movement simulating the motion of a step of a natural limb is accomplished. The above described forward movement of the right leg 2 is stopped at the proper 20 moment and in the proper position to receive the weight of the body of the wearer for the next step with the left leg by the back check 4 which comes in contact with the padded end of the slot 12.

30 It is apparent that in walking the leg 2 is always under control and may be brought forward by means of the straps 9 and 5, the latter being directly secured to the back check 4 which is in turn secured to the said 35 leg 2. It is also evident that when standing the forward movement of the hollow stump 1 is prevented and the limb is held rigid by means of the check 4.

Having thus described my invention what

I claim as new and desire to secure by Letters Patent is—

An artificial knee joint comprising a leg portion having vertical extensions secured to each side of the upper end thereof; a knee bolt rigidly secured between the upper ends 45 of the vertical extensions; a stump portion pivotally secured to the knee bolt and having a horizontal slot with a roller therein in the front portion, and a vertical slot with a padded lower end in the back thereof; a 50 retaining strap secured to and encircling the upper portion of the stump; a back check comprising upper and lower vertical portions and a central horizontal portion, the lower vertical portion being rigidly secured to the back of the leg portion and adapted to engage the lower padded end of the vertical slot in the back of the stump and the upper vertical portion being adapted 55 to engage the knee bolt within the hollow stump; a strap secured to the horizontal portion of the back check and adapted to pass over the roller in the horizontal slot in the front portion of the stump and under the retaining strap secured to the upper portion of the said stump; and shoulder straps secured to the back of the stump and adapted 60 to pass over the shoulder of the wearer and to engage the upper end of the strap secured to the horizontal portion of the back 65 check.

In witness whereof I hereunto set my signature in the presence of two subscribing witnesses.

CLYDE A. AUNGER.
